US00D978348S

(12) **United States Design Patent** (10) Patent No.: **US D978,348 S**
(45) Date of Patent: **** Feb. 14, 2023**

(54) **DRIVE DEVICE FOR A MEDICAL INSTRUMENT**

(71) Applicant: **Auris Health, Inc.**, Redwood City, CA (US)

(72) Inventors: **Casey Teal Landey**, San Francisco, CA (US); **Jeffrey C. Weintraub**, San Carlos, CA (US); **Bruno Richet**, Berkeley, CA (US); **Francois Pierre René Dransart**, San Francisco, CA (US); **Jaeyeon Kwon**, San Francisco, CA (US)

(73) Assignee: **Auris Health, Inc.**, Redwood City, CA (US)

(**) Term: **15 Years**

(21) Appl. No.: **29/701,988**

(22) Filed: **Aug. 15, 2019**

(51) LOC (14) Cl. **24-02**

(52) U.S. Cl.

USPC **D24/138**

(57) **CLAIM**

The ornamental design for a drive device for a medical instrument, as shown and described.

DESCRIPTION

FIG. 1 is a top, front, right perspective view of a first embodiment of a drive device for a medical instrument; FIG. 2 is a bottom, rear, left perspective view of the first embodiment;

FIG. 3 is a front view of the first embodiment;

FIG. 4 is a rear view of the first embodiment;

FIG. 5 is a left view of the first embodiment;

FIG. 6 is a right view of the first embodiment;

FIG. 7 is a top view of the first embodiment;

FIG. 8 is a bottom view of the first embodiment;

FIG. 9 is a top, front, right perspective view of a second embodiment of a drive device for a medical instrument;

FIG. 10 is a bottom, rear, left perspective view of the second embodiment;

FIG. 11 is a front view of the second embodiment;

FIG. 12 is a rear view of the second embodiment;

FIG. 13 is a left view of the second embodiment;

FIG. 14 is a right view of the second embodiment;

FIG. 15 is a top view of the second embodiment; and,

FIG. 16 is a bottom view of the second embodiment.

The broken lines illustrate portions of the drive device for a medical instrument and form no part of the claimed subject matter.

1 Claim, 12 Drawing Sheets
